UNITED STATES PATENT OFFICE.

HERMANN GRÖSSLER, OF BERLIN, GERMANY.

TYPE-WRITER.

No. 900,525.

Specification of Letters Patent.

Patented Oct. 6, 1908.

Application filed January 9, 1908. Serial No. 410,028.

To all whom it may concern:

Be it known that I, HERMANN GRÖSSLER, a subject of the Emperor of Germany, residing at Revalerstrasse 2, Berlin, Germany, have 5 invented certain new and useful Improvements in Type-Writers; and I do hereby declare the following to be a full, clear, and exact description of the invention, such as will enable others skilled in the art to which 10 it appertains to make and use the same.

This invention for improvements in key-operating mechanism for type writers and similar machines has for its object to enable the writing to be effected more easily and rapidly than hitherto and consists in an electrical actuating device comprising an electro-magnet provided with a core operatively connected with each key lever, a normally open energizing circuit, and means for closing the 15 circuit adapted to be placed on the finger of the operator.

Devices for operating the keys of typewriters are already known, in which an electric current is employed. With these devices the typist makes use of a contact pin, which is applied to the key or the typist actuates different contact buttons. In the case of the former method the speed at which the writing is effected is considerably reduced in 20 comparison with that done with machines having the ordinary key-operating mechanism. The latter method involves a greater expenditure of work, as the contact buttons must be moved in order to make contact. 25 All these disadvantages are avoided with the present invention, the keys carrying contact pieces, which are bridged over by means of metal caps or thimbles placed on the fingers of the typist. The slightest contact with the 30 key is sufficient for closing the circuit.

The invention is illustrated in the accompanying drawing.

The key *b* is touched by a metal piece *h'* without which there is no flow of current. 45 This metal piece *h'* is formed similarly to a thimble and when the key *b* is touched bridges over the two contact plates *c* and *c'*. One of the contacts for example *c* is conductively connected with the key lever *a*, while 50 the other contact *c'* is connected with the wire *i* that leads to an electromagnet *e*. If

both contacts *c* and *c'* be touched with the thimble *h'*, the magnet *e* is excited. The current flows from the battery *g* through the wire *k* to the key lever *a* and thence to the 55 contact piece *c* of the key. From the contact piece *c* the current flows through the thimble *h'* to the contact piece *c'* and through the wire *i* to the magnet *e*. After leaving the magnet *e* the current returns to the battery 60 through the wire *l*. When the magnet is energized the core or armature *d* carried by the key lever is attracted, and in this way the key lever is fully depressed, whereby the type corresponding to the key lever *a* is impressed 65 on the paper that is to be written on.

What I claim and desire to secure by Letters Patent is:—

1. In combination with a typewriting machine a pivoted lever, a key thereon, a pair 70 of contacts thereon, an electric line connecting said contacts, an electro magnet, and a source of current connected in series in said line and a plunger for said electro magnet, said plunger being connected with said lever. 75

2. In combination with a typewriting machine, a pivoted lever, a key thereon, a pair of contacts thereon, an electric line connecting said contacts, an electro magnet, and a source of current connected in series in said 80 line and a plunger for said electro magnet, said plunger being connected with said lever, said contacts being adapted to be connected by a conducting means carried by the finger of the operator of the machine. 85

3. In combination with a key of an electrical typewriting machine, a pair of contacts on said key, a plunger depending from said key, an electro magnet adapted to attract said plunger, a source of electrical current and a line connecting said contacts, said source of current and said electro magnet being connected in series between said contacts in said line. 90

4. In a typewriting machine, a key, an 95 electric circuit having both its terminals on said key, a key-operating magnet in said circuit, and means carried by the finger of the operator to connect said terminals and complete said circuit, thereby energizing said 100 magnet.

5. In a typewriting machine, an electric

circuit, a key lever, a key, and an electro-
magnet arranged in said circuit, electrically
separated terminals on said key, and means
carried by the finger of the operator to con-
5nect said terminals and thereby complete
said circuit and energize said magnet to
cause the latter to operate said lever.

In testimony whereof I have affixed my
signature in presence of two witnesses.

HERMANN GRÖSSLER.
